United States Patent Office.

JOSEPH W. BRANHAM, OF FRANKLIN, INDIANA.

Letters Patent No. 76,045, dated March 31, 1868.

IMPROVEMENT IN DRAUGHT-REGULATORS.

The Schedule referred to in these Letters Patent and making part of the same.

TO ALL WHOM IT MAY CONCERN:

Be it known that I, JOSEPH W. BRANHAM, of Franklin, in the county of Johnson, and State of Indiana, have invented a new and improved Draught-Regulator; and I do hereby declare that the following is a full, clear, and exact description thereof, which will enable others skilled in the art to make and use the same, reference being had to the accompanying drawing, forming part of this specification.

This invention relates to a new and improved method of constructing dampers or draught-regulators for furnaces, whereby the draught is more nicely regulated, and whereby they are more fire-proof. It consists of an iron frame, partly closed upon the upper end by sheet iron, provided with grooves in the side of said frame, in which a damper moves up and down. To said damper is pivoted a handle or lever, said lever being pivoted also to one side of said frame, by means of which said damper is moved, said damper being held in any position in its upward or downward movement by a pawl pivoted to said frame, and fitting into teeth in said handle or lever.

The drawing represents a front view of my invention.

A is the frame; B, the iron sheet, closing upper half of said frame A. C is a metallic damper. L is the lever or handle by means of which damper C is moved. a are hooks or buttons, by which frame A is secured to mouth of furnace. P are handles, by which buttons a are turned. e is the pivot on the damper C, upon which lever L turns. a' is a pivot on frame A, upon which lever L turns. H is the handle of lever L, by means of which lever L is operated, and damper C raised. d is a pawl, pivoted to frame A by pivot e', which, engaging in notches h, holds the lever L, and through the lever L, the damper C, in any position. h are notches in lever L, in which pawl d falls.

The frame A is a square or oblong square metallic frame, the sides of which are provided with grooves, in which the damper C moves. About one-half of the upper portion of said frame A is closed by an iron sheet, B, over which the damper C slides when the said damper C is being opened or moved upward. Upon said frame A, and passing through the same, are hooks or buttons, a, provided on the other side with handles, P, by means of which said buttons are turned, and by means of which said buttons a, said frame A is held in or secured to the mouth of a furnace or fire-box. Upon the damper C, and near the upper edge of the same, is pivoted the lever L. Said lever L is provided with a slot, through which is the pivot a', upon which said lever L turns, the object of same being that the lever L may move freely in any position of the damper C, to which said lever is attached by pivot e. Said lever L terminates in a handle, H, by the raising or lowering of which the damper C is either lowered or raised. To an upper corner of the frame A is pivoted a pawl, d, which engages in the teeth h of the lever L, thereby holding the damper C in any desired position, so as to admit more or less air to the fire in the furnace.

The operation is readily seen from the drawings.

The advantages of a damper or draught-regulator, constructed as above described, are, that by means of the same any desired quantity of air may be admitted to the fire, and by the air being admitted to the fire from the bottom, the grate-bars are less liable to injury, and when closed at any time the danger from fire is greatly lessened.

I claim as new, and desire to secure by Letters Patent—

The draught-regulator, constructed as described, consisting of the frame A, having the sheet B and the damper C, to which the inner end of the notched lever L is pivoted, having its fulcrum upon the side of the frame A at a', said damper being held in any desired position by means of the pawl d engaging with the notches h of the lever L, as herein described, for the purpose specified.

JOSEPH W. BRANHAM.
